UNITED STATES PATENT OFFICE.

GEORGE W. BAKER, OF COCHRANTON, PENNSYLVANIA.

BEDSTEAD-FASTENING.

Specification of Letters Patent No. 24,085, dated May 24, 1859.

To all whom it may concern:

Be it known that I, GEORGE W. BAKER, of Cochranton, in the county of Crawford, State of Pennsylvania, have invented a new and Improved Bedstead-Fastening; and I do hereby declare the following to be a full and exact description of the same, reference being had to the accompanying drawings and the letters of reference marked thereon.

Figure 1 represents my "fastening" adjusted in order.

A is the "bedstead post," B, B, the "rail." *i, i* is a mortise in the post larger (*i. e.* longer) than the "tenant" H, H, of the "rail."

E is an iron box with a circular cavity in its side. (See O, Fig. 2.) In this cavity the round head P of the hook D is placed so that the end s of the hook will move freely up and down; this box E is screwed on to the post A with the cavity side of the box against the rail B, B, thereby keeping the

hook D in its place. On the convex side of the box E is a slot m in which the shaft of the hook D works.

F is a toothed rack screwed on the shoulder of the rail, and in which the end s of the hook D "hooks," and when any weight is placed upon the rail B, B, it drops down in the mortise *i, i*, in the post, thereby increasing the distance between E and F which draws on the hook D thereby drawing the rail B, B, and the post A more tightly together the more weight is added on the rail B, B.

What I claim as my invention and desire to secure by Letters Patent is—

The box E, the hook D and the rack F when the same are used and combined substantially in the manner described and for the purposes set forth.

GEORGE W. BAKER.
